CASTING FISH REEL WITH LEVEL
WINDING MECHANISM

Sam H. Breedlove, Columbus, Ga.

Application May 1, 1947, Serial No. 745,261

3 Claims. (Cl. 242—84.4)

1

This invention relates to a multiplying casting reel and particularly to improvements in level winding means, and means for effecting constant lubrication of all moving parts.

A principal object of the invention resides in furnishing a mechanism with a rocking lever for leveling the line winding, and an arcuate plunger therefor contained in a similarly shaped guide tube and a cam, which cam and plunger arrangements supplies actuating power for the rocking lever. By means of this mechanism the life of the reel is considerably increased.

Another feature of this invention resides in furnishing constant self lubrication and shielding from abrasives. This is obtained by enclosing all gearing and furnishing seals and shields for all friction points located inside and outside of the housing. By constant lubricating and shielding from abrasives by means of special sealing devices, the life of the reel is lengthened considerably.

These and other objects and advantages of my invention will be understood from the subjoined description with the aid of the attached drawings.

One embodiment of the invention is illustrated on the drawings wherein:

Figure 1 is an axial section of the reel;

Figure 2 is an end elevation as seen from the right of Figure 1;

Figure 3 is a vertical section on a plane along line 3—3 of Figure 1;

Figure 4 and Figure 5 are respectively, a front elevation of the level winding lever and a side elevation thereof;

Figure 6 is a sectional view of an oil seal; and

Figure 7 is an axial section of a leveling gear and eccentric cam running freely on a stub shaft.

Like numerals denote the same details in the different views of the drawings.

The reel housing is composed of three flat plates of metal or plastic material, one central plate 10 and two end plates 11 and 12 held together in spaced relation by bracing rods 13 which extend from end to end of the housing. The plates 10 and 11 are placed a distance apart to hold the spool proper 14, while plates 10 and 12 with a cylindrical flange 12a provide a closed chamber for gears. Leak proof gaskets 16 are furnished at the housing joints and edges of said plates forming a leak proof housing.

About midway between the plates 10 and 11 the housing is secured to a mounting plate 17 secured by rivets or the like to the bracing rods 13.

2

The spool 14 consists of a pair of saucer shaped disks 20 with their peripheral edges bent outwardly and connected by a straight shaft 21 which is reduced in diameter outside of the disk 20 into a left hand spindle 22 and a right hand spindle 23. The end of spindle 23 is journaled in a socket formed in a thimble shaped bearing cup 24, which is threaded into the outer side wall of the plate 12 and provided with a shoulder 24a, between which and the plate 12 are inserted a number of shims 25 to allow for the adjustment of the bearing 24 to compensate for any end play of the shaft.

For the left hand spindle 22, a sleeve-like bearing 26 is furnished, similarly threaded in the left side plate 11, the outer end of said bearing being exteriorly threaded for receiving an adjusting cap 27 for adjusting end play of the spindle 22 and spool shaft 21. The inner end of the bearing 26 is enlarged in diameter as at 26a to receive an oil seal 28 as seen in Figure 6.

The oil seal 28 which is provided around all moving parts extending thru the walls of the housing, consists of a metal cup 30 fitting around the spindle 22, seen in Figure 6, and containing a washer or ring 28a made of soft, flexible material, adapted to close up all openings to prevent leakage of the lubricant and retaining it a considerable length of time in the housing. The oil seal may be of the spring loaded type and of antifriction nature in order to prevent undue load, but to permit free and easy turning of moving parts.

Other oil or lubrication seals consisting of rings or gaskets 16 of felt or rubber or similar material, are used between the edges of plates 10 and 12 and other openings of the housing.

Thus a leak proof gear chamber 34 is provided which is filled with lubricant up to a level 34a where a plug 35 seals a filling opening formed in the wall 12 of the housing.

In this sealed chamber 34 are contained all gears for winding up and placing in level layers, the line on the spool 14. If the lubricant in the gear case does not reach above the level line 34a, the gears will receive a splash of lubricant every time the fisherman makes a cast; but the gears will run in a constant bath, if the gear case is completely filled with oil or other lubricant.

As already stated, the principal object of the invention is the provision of the means for obtaining a level winding of the layers of line on the spool. The mechanism for accomplishing this consists of a guide having the form of an angled line lever 37, which has its longer arm

37a provided with an eye 37' adjacent to its free end through which the line L is threaded. The lever is pivoted, as at 38, to a bracket 39, secured on a mounting plate 17, which supports the reel housing. This mounting plate 17 is riveted to the cross stays or rods 13 of the housing. The free end of the horizontal arm 37b is formed with a longitudinal slot 40 in which engages a cross pin 41a carried on the free end of a flexible wire actuating plunger 41 for said swinging lever 37, 37b. This plunger 41 is arcuate or semi-circular in contour and is mounted to slide in a similarly shaped guide tube 42, open at both ends and rigidly secured in an opening in the middle housing plate 10 by a welded bracket 43, in such a manner that the two ends, one inside the gear casing and the other end outside thereof, are each situated in a position for actuation by cam 52 always slightly above the lubricant level 34a.

The outer end of the said arcuate guide 42 is positioned under the slot in the arm 37b of the lever 37 and is provided with an oil seal 28 as already described. The plunger 41 is of greater length than the guide tube 42 so that, in the normal position of the parts, both ends protrude above the open ends of the guide tube 42, as best seen in Figure 1. A tension spring 30 has its ends secured to the arm 37b and the stay rod 13 respectively, tending to swing the lever 37 to the right in Figure 1.

A stub shaft 46 is carried, in a suitable bearing 47 in the right hand plate 12 of the housing, and has on its outer end a double ended crank 48. This bearing 47 is provided with an oil seal 28, as shown in Figure 6. On the inner end of the stub shaft 46 is secured a spool rotating gear 49 and at the side thereof there is secured a line leveling gear 50. Accordingly both are rotated at the same angular speed as the crank 48. The spool rotating gear 49 meshes with the gear pinion 51 therebelow which is fixedly mounted on the spool spindle 23. The opening in the middle wall 10 is also provided with an oil seal 28 around the spindle 23.

The driven spool rotating pinion 51 is smaller than gear 49 thereby increasing the rotation of the latter, while the gear 50 is in mesh with a larger, line leveling gear 53 which carries a cam 52. The eccentric cam 52 and the driven gear 53 are both mounted on the stub shaft 54, to run freely thereon. Said stub shaft 54 is fixed on the plate 12 of the housing. This cam 52 governs the position of the plunger 41 as the inner end of the latter always is in contact with the surface of the cam 52 and in this manner in a one-half revolution of the cam 52, from its position as shown in Figure 1, the plunger is pushed through the guide 42, and acts to rock the lever 37 on its pivot 38, so that the arm 37a is shifted from its centered position toward the left, and thereby guiding the line L evenly along the spool 21. When the cam 52 is turned through the other half revolution the plunger 41 is retracted by the action of the spring 30, thereby rocking the lever 37, to shift the arm 37a in the opposite direction.

At the left end of the spool 21 a ratchet wheel 56 is shown which is secured on the spindle 22. On the plate 11 is fastened a latch spring 57 resting on the teeth of the ratchet wheel 56, in order to hold the spool locked to prevent unreeling thereof. On this spring 57 is carried sliding button 58 whereby the spring 57 is released to free the spool when the fisherman is ready to throw the line.

The operation of the device is the following:

In order to wind up the fish line on the spool, the crank 48 is turned causing the winding gears 49 and 51 to rotate and the spool 21 with it. Since the gear 49 is larger in diameter than the gear 51, the ratio of revolution of the spool 21 is considerably increased over that of the crank 48. At the same time the revolution of the layer leveling gear 53 which has a smaller diameter than that of the winding gear 50, reduces the speed of revolution of the latter, causing a slow swinging motion of the leveling lever 37. Thus it will be seen that while the spool winding speed is very high, the speed of the level winding mechanism is considerably lower. This reduction in the winding drive ratio is necessary in order to place the fish line on the reel in uniform layers across the same and in true circles around it.

The size and shape of cam 52 is therefore of great importance in order to lay the fish line 38 evenly on the reel while turning it by the crank 48.

It will be evident, in order to obtain a smooth reeling and unreeling of the spool, that the lubricant in the casing 34 must have a certain viscosity and lightness.

The running of all moving parts of the reel in a bath of oil as described reduces wear, and assures that all parts run smoothly, preventing dynamic unbalance, thus assuring long life and use of the reel. By means of this constant and automatic lubricating the carrying of an oil can for such purposes is unnecessary.

It is to be understood that the invention as herein disclosed may be varied from the details described and shown without departure from the spirit of the subjoined claims.

I claim:

1. A fishing line reel comprising a frame, a winding spool revolvably mounted therein, a sealed compartment at one end of the frame, a supporting shaft for said spool extended at one end into said compartment, a gear train within said compartment operatively coupled with the said end of said shaft, crank means for actuating said train, said compartment being adapted to contain a fluid lubricant, a line guide, means pivotally supporting said guide for movement relative to the spool, a reciprocable guide actuator having one end operatively coupled with the guide and a second end extending into said compartment, means within the compartment connected with said second end for effecting movement of the actuator upon actuation of the gear train, an operative coupling between the last named means and the gear train, the said last named means comprising a rotatably mounted cam turned by said gear train, said actuator comprising a flexible wire, and a tubular sheath for said wire having one end within the compartment in close proximity to the periphery of said cam, the wire having an end extended from the said end of the sheath and in contact with the periphery of the cam.

2. A fishing line reel comprising a frame, a winding spool revolvably mounted therein, a sealed compartment at one end of the frame, a supporting shaft for said spool extended at one end into said compartment, a gear train within said compartment operatively coupled with the said end of the said shaft, crank means for actuating said train, said compartment being adapted to contain a fluid lubricant, a line guide comprising a bell crank member having a long arm having a guide eye and a short arm having

a slot, means pivotally supporting the bell crank member with the long arm arranged for movement of the guide eye lengthwise of the spool, a guide tube having an end extending into the sealed compartment and a second end adjacent to said short arm slot, a plunger in the form of a flexible wire extending through and reciprocable in said tube, means carried by an end of the wire for loose connection in said slot, the other end of the wire extending into the compartment, gear means in the compartment in driving connection with said spool shaft, a crank for rotating said gear means, a cam rotatably supported in the compartment and having driving connection with said gear means to be rotated by the latter, the said other end of the wire being pressed against the working face of the cam, and spring means connected with, and urging swinging movement of, said crank member in the reverse direction to that in which it is moved by the cam actuated wire.

3. A fishing reel comprising a frame, a winding spool revolvably mounted therein, a sealed oil and gear compartment at one end of the frame, a supporting shaft for the spool having one end extended through an oil tight bearing into the compartment, a gear train in the compartment operatively coupled with said shaft end, crank means for rotating the gears, a cam rotatably supported in the compartment, means connecting the cam with said gears for rotation thereby, a mounting plate for the reel and having the frame secured thereto, a level winding crank member pivotally mounted on said plate for swinging movement in a plane paralleling the axis of the spool, said crank having a long arm disposed across the axis of the spool and a

short angular arm extending substantially lengthwise of the spool, the long arm having a line guide eye, a tube having an end extending through and rigidly secured to a wall of said compartment and opening at said end into the compartment adjacent to and directed toward the working face of said cam, the other end of said tube being adjacent to said short arm, a flexible plunger wire in and extending through the tube and projecting from each end thereof, an oil seal in the said other end of the tube about the wire, a loose coupling between said short arm and the adjacent end of the wire, the other end of the wire being engaged against the working face of the cam, and a spring operatively connected between an arm and a fixed part of the reel for swinging the crank member in one direction.
